[57] ABSTRACT

A device for controlling the tension of a length of wire as it is being unwound from a spool across one end flange thereof. A continuous, looped flexible monofilament member is sandwiched between two coaxially secured discs extending around the circumference thereof with the extremities of the flexible member protruding radially beyond the periphery of the discs. The sandwiched portions of the flexible member are spaced radially from the axes of the discs. The protuberant extremities of the flexible member are severed to produce a plurality of flexible separated fingers or strands. The assembled discs can be mounted on a flange of the spool with the wire extending through the fingers to control tension of the wire as it is unwound from the spool, the device remaining stationary on the spool.

DEVICE FOR CONTROLLING TENSION OF WIRE DISPENSED FROM A REEL

BACKGROUND OF THE INVENTION

1. Field of the Invention

This invention relates to wire tension control devices, and more particularly, to a control device of the character described adapted to be mounted on the end plate or flange of a wire spool for controlling the tension of the wire as it is being unwound from the spool.

2. Description of the Prior Art

Spools of wire commonly are used in many fields for storage of the length of wire retained thereon and to facilitate convenient unwinding of the wire without twisting or kinking, when winding coils or the like. In many instances, it is desirable to unwind the wire across one end flange of the spool while the spool rests on the opposite end flange thereof conveniently adjacent a coil winding machine, for instance. During unwinding of the wire, the spool remains stationary, as opposed to an alternate method of unwinding the wire in which the spool is mounted on a shaft, and the wire is unwound tangentially while the spool rotates. While it is generally more convenient to unwind the wire across the end flange of the stationary spool, such method of unwinding results in the wire becoming tangled and distorted as it is being unwound.

It is known to provide devices for attachment to the end flange of a spool for anti-kinking purposes. In U.S. Pat. No. 3,323,960, there is disclosed an impedance element including a plurality of radially extending thin, flexible members through which the wire is forced as it leaves the spool. This device is formed by winding a length of flexible, filament material upon a ring so that a multiplicity of lengths of wire across a corresponding number of diameters of the ring is realized. During formation of the wire-wound ring, a central opening or clear area is produced by the turns to provide a passageway therebetween which corresponds with the passageways provided in the two discs thereafter assembled on either side of the filament ring. Upon assembly of the discs the turns are severed at their extremities beyond the peripheries of the discs to produce a multiplicity of fingers or strands which serve to impede kinking of the wire strand as it is unwound from a spool to which the device is attached.

The device of said patent has certain inherent disadvantages because of the method by which the same is formed. Because the wire-like member is wound across a multiplicity of diameters of the ring, there is a build-up of material at the center of the ring due to the cross-overs of the diameters proximate the center. This build-up of material produces an upstanding formation which hampers proper and desirable securement together of the discs over the wound strands. Furthermore, because each wire strand is repeatedly wound completely across a diameter of the disc, a large amount of filament material is required.

SUMMARY OF THE INVENTION

Accordingly, it is an object of this invention to provide a device for controlling the tension of a length of wire as it is being unwound from a spool across one end flange thereof, said device formed of a continuous looped flexible mono-filament member sandwiched between two discs which are coaxially secured, and extending around the circumference thereof, with the ex-

tremities of the flexible member protruding radially beyond the periphery of the discs, the sandwiched portions of the flexible member extending only partially toward the aligned centers of the discs so as to prevent the build-up of strand material at the center of the discs. Further, a significant reduction in the quantity of filament material utilized as compared to prior art devices is realized.

Other objects and advantages of the invention will appear to those skilled in the art from the ensuing disclosure.

BRIEF DESCRIPTION OF THE DRAWING

FIG. 1 is a plan view of the tensioning device embodying the invention.

FIG. 2 is a sectional view of said device taken along the line 2-2 of FIG. 1 and in the direction indicated generally.

FIG. 3 is a plan view of said device partially assembled and with portions broken away to show disposition of the filaments on the retaining ring.

DESCRIPTION OF THE PREFERRED EMBODIMENT

Referring to the drawing, the wire-tensioning device embodying the invention is designated generally by reference character 10. Said device 10 includes a securing ring 12, a plurality of protruding wire-like extension fingers or strands 14 and a pair of disc members 16 and 18, coaxially secured on opposite sides of the ring 12 as a sandwich. The ring 12 and the disc members 16, 18 may be formed of any suitably rigid material, such as, a heavy-weight paperboard. Each of the discs 16, 18 is provided with a central aperture 20, 22, respectively, to enable securement of the assembled tensioning device 10, in a well-known manner, to one end flange of a spool for retaining wire wound thereon.

The tensioning member 10 is constructed in the manner illustrated in FIG. 3. A continuous length of flexible mono-filament material 17 is looped so that the loops 17', 17'', etc., are disposed around the circumference of ring 12 with at least a portion 19', 19'', etc., of each of the loops 17', 17'', etc., extending beyond the perimeter of ring 12. The looped filament 17 is secured to one side of ring 12 by adhesive 26 so that the filament 17 is retained thereupon. The bound portions 28 of the looped material 17 which are retained upon the ring member 12 extend only partially toward the aligned centers 20, 22 of the discs 16, 18, such that a central unoccupied space 29 remains between the center of the discs and the imaginary circle 29' defined by the inwardly facing ends of loops 17', 17'', etc. The unoccupied space 29 is illustrated in FIG. 3 and is defined by the radius 30. Thus, there is no overlapping of the loops 17', 17'', etc., across the center of the discs 16, 18 and therefore, there is no build-up of filament material 17 at this central location. The loops 17', 17'', etc., are wound and secured upon disc 12 such that a uniform thickness of filament material 17 is present around the entire circumference of the ring 12.

After assembly of the loops 17', 17'', etc., upon ring 12, the ring is secured to disc 18 by suitable adhesive and disc 16 is secured to the opposite side of the assembly of ring 12 and disc 18. Upon securement of the loops 17', 17'', etc., between discs 16, 18, the portions 21 of filament 17 are sandwiched between said discs. The radial dimension of discs 16, 18 preferably is the

same as the outside radius of the ring 12 so as to enhance the rigidity and stability of the ring and discs one relative to the other. Thereafter, the extremities 32 of each loop 17', 17'', etc., are severed to produce a plurality of wire-like fingers or strands 14 which extend beyond the perimeters of discs 16, 18.

It may be noted that the density of strands 17 may be controlled by the number of loops or turns made. The strands may be formed of a suitable mono-filament synthetic plastic.

I claim:

1. A disc-like device for controlling the tension of a length of wire as it is being unwound from a spool across one end flange thereof, said device comprising, a retaining ring, a plurality of loops of flexible mono-filament material secured to one face of said ring and extending beyond the circumference thereof, and a pair of discs coaxially secured to either side of said ring to sandwich portions of said loops and said ring therebetween, the sandwiched portions of said loops extending only partially toward the center of said device to provide an unoccupied space between the center of the device and the ring.

2. A device as claimed in claim 1 in which said loops are formed from one continuous length of material.

3. A device as claimed in claim 1 in which said loops are adhesively secured to said one face of the ring.

4. A device as claimed in claim 1 in which the radial dimension of the discs and the outside radial dimension of the ring are substantially similar.

5. A disc-like device for controlling the tension of a length of wire as it is being unwound from a spool across one end flange thereof, said device comprising, a retaining ring, a plurality of fingers of flexible mono-filament material secured to one face of said ring and extending beyond the circumference thereof, and a pair of discs coaxially secured to either side of said ring to sandwich portions of said fingers and said ring therebetween, the sandwiched portions of said fingers extending only partially toward the center of said device to provide an unoccupied space between the center of the device and the ring, said fingers extending radially around the periphery of the device.

6. A device as claimed in claim 5 in which said fingers are adhesively secured to said one face of the ring.

7. A device as claimed in claim 5 in which the radial dimension of the discs and the outside radial dimension of the ring are substantially similar.
